CLAIM

The ornamental design for a two-part flower vase, as shown and described.

DESCRIPTION

FIG. 1 is a front perspective view of a design for a two part flower vase showing my new design;

FIG. 2 is an exploded perspective view thereof;

FIG. 3 is a top plan view thereof;

FIG. 4 is a rear elevational view thereof, the front elevational view being a mirror image thereof;

FIG. 5 is a right side elevational view, the left side elevated view being a mirror image thereof; and,

FIG. 6 is a bottom plan view thereof.
